ROOF AND ELEMENTS FOR THE CONSTRUCTION THEREOF

William L. Rowe, New York, N. Y., assignor to
 Johns-Manville Corporation, New York, N. Y.,
 a corporation of New York

Application March 16, 1931, Serial No. 522,814

3 Claims. (Cl. 108—33)

This invention relates to a roof built of slates, shingles or tiles of cut sheet material natural or fabricated, hereinafter referred to as shingle units, to shingle units therefor, and to a fastener 5 clip for conjoining otherwise free ends or edges of such shingle units. The shingle units may be rigid, flexible or semi-flexible fabricated composite plates, shingles, or tiles of any sheet material suitable for roofing.

- 10 One object of this invention is to provide for the rapid and accurate construction of well-spaced and fastened courses of shingle units, and to provide for the anchorage of the exposed or free side or end of shingle structures against 15 wind or storm stresses, or in opposition to any other tendency to displacement in such a way as to avoid direct attachment of the anchor or clip relied upon to the roof deck or sheathing. A further object of the invention is to provide an 20 appliance for the purpose indicated capable of rapid and successful application by the relatively unskilled and serving, in combination with shingle units of predetermined form, to aid placing them in a desired order on a roof deck. Another 25 object is to provide a clip device capable of easy application to shingles having holes, either made during erection or provided in uniform shingle units, which extend through only the uppermost 30 layer of the overlapped shingle units, but which shall nevertheless constitute, in place, a wholly reliable anchor or binder for the shingle units to which it is applied, which shall be of good appearance, and which shall enable a roof formed 35 of shingle units and said clips to be securely attached to the roof deck or sheathing by ordinary nails driven through underlying and concealed parts of the shingle units. Another object of 40 the invention is to provide a roof of overlapped shingle units in which the relation of overlapped areas to the exposed surfaces has been decreased without sacrifice of efficient protection against water seepage.

The invention will be explained with the aid 45 of the accompanying drawings, in which

Fig. 1 is an elevation of a detail of a roof laid in the so-called honeycomb-lap of hexagonal shingle units, parts being broken away to show underlying structures;

Fig. 2 is a detail section on the line 2—2 of Fig. 1;

Fig. 3 is a side elevation of one of the clips before application;

Fig. 4 is a section in plan on the line 4—4 of Fig. 3;

Fig. 5 is a front elevation of the clip shown in Fig. 3;

Fig. 6 is a plan of the clip shown in Fig. 3;

Fig. 7 is a corresponding plan of a modified form of one of the clips; 5

Fig. 8 is a plan of a detail of a roof showing one use of the device of Fig. 7;

Fig. 9 is an enlarged detail of one species of shingle unit illustrative of the genus of the invention; and 10

Fig. 10 is a detail showing a half shingle for a starting course.

Familiar practice in the construction of a roof of fabricated composite sheets, for example, asbestos and cement or other flat plastic aggregate sheet units, is to anchor down the otherwise free ends of the shingle units by a so-called storm anchor, usually a flange-headed soft metal nail or bolt placed head down, and threaded from beneath through registering holes in the 20 free ends of overlapped shingle units, for example according to the United States patent to Wm. B. Black No. 1,775,085, September 9, 1930. This necessitates applying the shingle units over a placed anchor of this kind by the sense of 25 touch, since the entrance of the point of the anchor into a hole for it is from beneath or behind the perforated shingle unit. This has to be done in relation to two of the overlapped units. This operation is slow and difficult. When 30 placed, and the shingles nailed at their top ends or remote sides, these anchors are clinched over and hammered down. Uniformity of the exterior appearance of the anchors and avoidance of breakage of the shingles is not attained except by skilled workmen. 35

Referring now to Figs. 2 to 6, this invention provides for fastening together the overlapping edges or ends of superposed shingle units by the metal clip 1, which in a preferred form comprises 40 a U-shaped malleable metallic instrument having a base 2, which may be flattened and tapered, an integral upturn 3, and overlying top 4, the length of the portion 3 being such as to bridge the butts or overlapped edges of two shingle units 10, 10 each 45 braced between the base 2 and top 4. Separation of the shingle units is prevented by the tensile strength of portion 3 and stiffness of the base 2 and top 4, which preferably is retained in place by penetration through and clinching of its end 5 50 under the upper shingle 10 through a hole a: This is made possible by integrally forming the upper arm 4 of the clip 1 with an integral end 5 made as a downturned hook. As shown in Figs. 5, 5 and 6, the hook 5 may be swaged to a taper 55

in a plane perpendicular to that of the portions 3 and 4 to permit the hook portion 5 to bend more easily in the plane of the portions 3 and 4 than in another dimension. To facilitate applying the 5 clip the base 2 may be swaged to a taper in a plane perpendicular to the portion 3 so as to terminate in an expanded wedge-shaped point at 6. For hard shingles, the holes *a* may be pre-formed according to a gauge or jig, and clinching 10 of the points 5 may comprise inserting them through the hole *a* and finishing the structure by a hammer blow on the top 4, after the clip is placed with its wedge end 6 and base 2 under the free end or side of the underlying shingle 10.

15 In some situations, as for an instance illustrated in Fig. 8, it is an advantage and convenience to the workman to displace the arms 2 and 4 from the same plane. For example, Fig. 7, the member 3 may be subjected to torsion, if desired by the 20 workman applying it, so as to turn off the base 2 to the left as shown, or to the right at an angle of 30° or thereabouts. In this case when the base 2 has been placed under the butt of one of the shingles 10^c for example, Fig. 8, the clip 1^a 25 may be fully entered under the shingle unit 10^c and the hook 5 brought over the hole in the overlapped shingle for entrance, as mentioned above.

The preferred material of manufacture for the 30 clips 1 or 1^a is an annealed wire, preferably a wire of a soft metal, such as copper, bronze or soft brass. I do not exclude manufacture of any soft metal such as wrought iron, or any of the malleable rustless ferrous or aluminum alloys; in many 35 cases ordinary iron or steel is a satisfactory material, especially if coated or galvanized.

In the preferred form, see Fig. 3, the center line of the hook 5 may be bent at an angle to the top 4 of about 60°, more or less, and the top 4 may be bent away from the portion 3 at an obtuse angle to provide a space between the point 5 and the point 6 at least equal to the thickness 40 of two superimposed shingle units.

As illustrated in Figs. 1 and 9, clips of the kind 45 explained are useful in many forms of construction, for example as illustrated by the construction shown, Fig. 1, of a honeycomb or fish-scale shingle lay, for which according to this invention shingle units 10 of lozenge or laterally symmetrical rhombic or scalene parallelogram form, 50 with one or more truncated corners, are provided with notches 12 near their truncated abutting lateral ends, and with holes *a* at a predetermined distance from the notch 12 at one end of the unit 10 for the clips 1, which are thus placed to one 55 side of the center line of the usually truncated lower points 20 of the outer of the lapped shingle units. At this place the shingle units have a three-ply overlap, Fig. 2.

The clips 1 may aid in the performance of placing 60 the shingles uniformly. For example, as shown in Figs. 1 and 9, the units are provided with symmetrically and accurately placed preperforated nail holes *d* near their truncated lateral ends capable of receiving a nail beyond the upper edge 65 of an underlying unit; after laying the first course of shingles, a second course may be placed with the aid of the clips 1 in position in the holes *a*, bringing into superposed relation the notches 12 and edge 20, and, if desired by alignment with notches 13, 14 in the upper inclined edges of the units 10 or 11, of the upper edges of the newly-placed 70 course so as to provide for a precalculated underlap of the upper inclined edges of the units, already laid, under the lower inclined edges of the 75 units being positioned. Referring to Fig. 9, in a

preferred form lower points of the units 10 are truncated at 20 and the two side points at 21, 21, equidistant from the vertical axis of lateral symmetry. The top angle may be truncated at 22, but merely to guard against irregular breaking 5 off of this point in shipment or otherwise. The truncation of the side points is related to the production of the proper lap of one horizontal row of shingles over the next below. The truncation of the lower point at 20, which primarily for improvement of visual appearance of the roof as a whole, is of service in securing proper spacing and alignment of the tiers of shingles with the aid of clips 1, as mentioned above, and of notches 12, 12, 12, 12, Fig. 9, laid with the severed edge on the line of the eave) are abutted laterally against each other with edges 21 in contact in any desired way. Thereafter all that need be done to align each shingle is to bring its lower point truncation 20 into register with the notches 12 which lie one on each side of the lateral abutment junction of two shingles of the laid tier, and to bring 30 the upper inclined long sides of the said shingle into register with one upper notch 13 of one lower shingle and an upper notch 13 of the adjoining lower shingle. This centers the side truncations of the upper shingle over the vertical axis of the 35 lower shingles and brings the long axis of the upper shingle into parallelism with the long axes of the underlying shingles. This avoids making any gauge marks on the roof.

In the device of Fig. 8, the notches 12 are replaced by the intersection of the edges of the lower lateral slope of the underlying unit with the truncated lower end of the overlying unit. The kind of shingle unit 10 herein disclosed contributes to increased economy of material without 45 sacrifice of the integrity of the completed roof against water seepage under gravity or wind pressures. Such seepage is resisted by the extent vertically and the extent horizontally of the overlap of one shingle over another; the 50 vertical extent of overlap required for this is less than the horizontal extent. In practice heretofore with shingle units having diagonal overlaps, so far as I am aware, an unnecessary degree of vertical overlap has been 55 provided for, whereas the horizontal overlap is barely sufficient for good function. This is a consequence of the usual design of such shingles with diagonal exposed edges at 90° to each other and 45° to the horizontal, with the remaining 60 edges of their generally quadrilateral shapes at equally high angles. When laid, if such shingles are sufficiently overlapped in a horizontal sense, their vertical overlap is unnecessarily large.

For any particular use, the degree of acuity of 65 the end angles of the rhombic or lozenge-shaped shingle unit 10 shown in Figs. 1 and 9, and herein recommended, may be determined by laying out a right triangle in which base and altitude are proportional respectively to the required vertical 70 and horizontal overlap, and making the shingle units so that the end angles are twice the angle so formed between the hypotenuse and altitude lines. Since the vertical overlap is to be less than the horizontal, these end angles are less 75

than 90°. As shown, the end angles are between 71° and 72°, so that, laid, the diagonal exposed edges are at angles of from 35° to 36° to the horizontal, and of the order 108° to 110° to each

5 other. In every part of the overlap between the shingles, the horizontal dimension of the overlap exceeds the vertical dimension of the overlap, for example substantially in the proportion of 17 to 12. The position of the end truncations of 10 the units 21 controls the actual dimensions of the overlap, but not the proportion between its vertical and horizontal dimensions.

15 As compared with practice in which the end angles are right angles, the saving of material for equal areas of roof covered amounts to about 8%. The more obtuse angle of the exposed edges of the lozenge shaped shingles contributes to a more pleasing architectural appearance.

20 Referring now to Fig. 2, in a preferred form of construction on a wooden deck *w*, this may first be covered with a suitable paper or felt *f*, a starting course of half-shingles 11, Figs. 1 and 10, laid at the eaves, and the courses comprised of units 10 applied and nailed to the sheathing *w* by nails 25 through the holes *d* as illustrated at *n*, Figs. 1 and 2, whereupon a second course and third course are laid to overlap to the left and right of the axis of lateral symmetry or center line of the units of the previous courses, as shown in 30 Fig. 1, shingle units cut on vertical lines being employed at the ends of courses. The lower end of the shingles of the second and third courses are interlocked to the preceding course by the clips 1 in proximity to the point of attachment 35 by the nails *n* of the preceding course, as illustrated in Fig. 1.

40 Clips of the kind explained are useful where it is desirable to connect together a second and third layer of shingle units in any form or lay of roofing units; for example in the lateral or Dutch lap mode of laying; or in the American or staggered overlap on horizontal or staggered courses; or indeed in any situation requiring a sound and convenient binding together of the 45 free ends or edges of overlapping units.

45 It will be observed that forces tending to separate shingles conjoined by these clips are resisted by the tensile strength of the portion 3, and that the bearing on the lowermost shingle of a pair 50 conjoined is the relatively long surface of base portion 2, whereas the bearing on the top shingle of the pair conjoined is the long surface of the top 4. The tie between the two shingles is thus effected by the tensile resistance of a strong connection over their edges between portions 2 and 55 4. These clips can be affixed after nailing the shingles down, and affixing them requires no loss of time by blind threading of a hole from behind the surface; the hooks 5 can be readily entered 60 from the face side of the shingle units into their holes *a*. Since it is not necessary to place the clips between successive nailings of shingles, the workman can lay and nail them very rapidly, and by placing the clips as a separate operation, 65 requires less time for this than if he had to alternate handling of nails and clips.

70 For the purposes of this specification, the matters described apply as well to and for the construction of a side wall, which is no more than a vertical roof, without change of construction or function.

I do not herein claim the species which involves the combination of my anchorage clips with a

side-lapped shingle unit of improved form described and claimed in my application Serial No 522,817, filed of even date herewith.

I claim:

1. Clip for shingle units formed of malleable 5 round wire and having a portion constituting a top and a portion constituting a base, said portions being bent at angles to the plane of an integral connecting portion, the base portion extending substantially at a right angle to said connecting portion and being flattened transversely to said plane to afford a wedge-like end portion, the top portion being at a greater angle to said connecting portion, said top portion having an inturned flattened hook in the plane of said connecting portion, said hook having an extremity inclined inwardly toward said connecting portion whereby the base may be located beneath the lower of two shingle units with the connecting portion juxtaposed to the edges of said units, and 20 the top may be bent down to position the hook within an opening in the upper unit, the extremity of the hook being automatically clinched about the wall of the opening due to the bending of its inclined extremity in contact with the surface of the lower unit so that said extremity lies between the units and extends toward the connecting portion.

2. Clip for shingle units consisting of malleable 30 wire and having a portion constituting a top and a portion constituting a base, said portions being bent at angles to the plane of an integral connecting portion, the base portion extending substantially at a right angle to said connecting portion and being flattened transversely to said 35 plane to afford a wedge-like end, the top portion being at a greater angle to said connecting portion, said top portion having an inturned hook in the plane of said connecting portion, said hook having a flattened, relatively wide extremity 40 inclined inwardly toward said conjoining portion whereby the base may be located beneath the lower of two shingle units, the connecting portion being juxtaposed to the edges of said units and the top may be bent down to position the 45 hook within an opening in the upper unit, the extremity of the hook being automatically clinched about the wall of the opening due to the bending of its inclined extremity in contact with the surface of the lower unit so that said extremity lies between the units and extends toward the connecting portion.

3. Roof comprising a deck and shingle units of substantially rhombic form having truncated ends and a truncated lower portion with notches ad- 55 joining the truncated ends and disposed adjoining the truncated lower portions of shingles of another course, nails securing concealed portions of the shingles to the deck, openings asymmetrically arranged in relation to lower truncated 60 edges of the units, a clip engaging each opening and a notch of an adjoining underlying unit, said clip having a base extending under the end of the underlying unit, a connecting portion 65 juxtaposed to edge surfaces of an underlying and overlying unit, a top extending over the exposed surface of an overlying unit and a hook in the hole asymmetrically arranged in the upper unit and having an extremity clinched under the 70 overlying unit and engaging the upper surface of the underlying unit.

WILLIAM L. ROWE.
